(57) **CLAIM**

The ornamental design for a combination wall cover and door stop, substantially as shown and described.

DESCRIPTION

The combination wall cover and door stop (also known as a wall cover and door bumper) in which the design is embodied is used to cover holes in walls created by a door knob or lever when the door is pushed, shoved or swung against the wall, and as a door stop used to absorb the energy of a door knob or lever when the door is pushed, shoved or swung toward the wall to prevent the formation of holes in the wall.

FIG. 1 is a top front perspective view of the combination wall cover and door stop showing my new design;

FIG. 2 is a top elevation view thereof;

FIG. 3 is a side elevation view with a corner centered in the view, all sides be identical;

FIG. 4 is a side elevation view with a side wall centered in the view, all sides be identical; and,

FIG. 5 is a bottom elevation view thereof.

The broken lines presented in the drawings are for illustration of structure and boundaries only and form no part of the claimed design.
